UNITED STATES PATENT OFFICE

2,527,056

COMPACT CABINET AND TABLE

Paul A. Cain, San Angelo, Tex.

Application May 5, 1947, Serial No. 746,013

1 Claim. (Cl. 312—162)

1

The present invention relates to combination tables and cabinets and it consists in the combinations, constructions and arrangements of parts herein described and claimed.

Generally, the invention consists of a cabinet structure which is adapted to take up a minimum of space and is especially adapted to modern apartments and the like wherein space is at a minimum. The cabinet is provided with a pair of outwardly extending doors each of which is provided with shelves or other storage space and within the cabinet is mounted a collapsible table top which is adapted to be pulled out and fastened to a pair of brackets which are normally folded within the cabinet but are hinged to extend outwardly to form a support for the table top member. The brackets are so arranged as to provide a maximum of leg and foot room. A novel arrangement is provided in the top of the bracket members for cooperatively locking the same to the table top when the latter is in extended position.

It is, accordingly, an object of the invention to provide a simple, compact, inexpensive and efficient combination cabinet and table.

A further object of the invention is the provision of a device of the character described wherein there is provided a maximum of leg and foot room when the table is extended.

A further object of the invention is the provision of a novel collapsible table top and support therefor.

A further object of the invention is the provision of novel means for locking the top to the supporting members.

Other and further objects of the invention will become apparent from a reading of the following specification taken in conjunction with the drawings, in which:

Figure 1 is a front elevational view of a device embodying the invention.

Figure 2 is a side elevational view thereof.

Figure 3 is a front elevational view of the device shown in Figure 1 in open position.

Figure 4 is a sectional view taken along line 4—4 of Figure 6 with the table top in open position.

Figure 5 is a view similar to Figure 4 showing the table top in folded position.

Figure 6 is a plan view, partly broken away, of the invention in open position.

Figure 7 is an enlarged sectional view taken substantially along line 7—7 of Figure 6, and

Figures 8 and 9 are enlarged detail views of the invention.

2

Referring more particularly to the drawings, there is shown therein a cabinet having a body portion 10 and having hinged thereto as indicated at 11 a pair of doors 12 each provided with a handle 13 and each having upon its inner side a plurality of shelves 14 and a partition 15 to provide convenient compartments therein.

Mounted within the back portion of the cabinet 13 by means of screws 16 or the like are vertically extending channel members or rails 17 at the sides thereof. Each channel member is L-shaped at its upper end as indicated at 18 and each is adapted to coact with a channel member or rail 19 hinged to the interior sides of the cabinet 10, as indicated at 20. Each channel 19 is provided with a bracket arm 21 attached adjacent the outer end thereof and hinged at its lower end as indicated at 22.

A table top comprising a series of slats 24 hinged at their under sides as indicated at 25 is adapted to ride upon the channel members 19. The channel members 19 have upwardly extending ridges 26 which are adapted to lie within grooves 27 formed in the under side of the slats 24.

The outermost slat 24 is provided with an operating handle 28. The horizontal section 30 of the channel arms 19 is, in each case provided with a series of staggered openings 31 for the reception of downwardly extending hooks 32 carried on the under side of the slats. The hooks 32 are so staggered in order to cooperatively engage the section of the rails through the openings 31.

In the operation of the device it will be apparent that upon opening the doors 12 to the fully extended position shown in Figure 3 there will be provided cabinet space within the cover members 12 and that thereupon the channel members 19 may be swung to outward position as shown in Figure 5 and that the handle 28 may then be grasped and pulled to a forward position as shown in Figure 4. With the parts arranged in this manner the hinged slats 24, which are normally positioned behind the rails 17 are drawn upwardly and outwardly by the handle 28 with the grooves 27 in the lower surfaces of the slats positioned over the upper edges of the upwardly extended flanges of the rails with the rails 19 open to the positions shown in Figures 4 and 5. With the slats positioned on the rails in this manner the hooks 32 extend downwardly through the openings 31 in the horizontally disposed flanges 30 of the rails thereby frictionally

securing the slats in the outwardly extended or operative position. In this position the slats form a table top that may be used as a desk, table, or the like.

The hooks 32 may then be engaged in the openings 31, the staggered relation of said hooks and openings providing for each hook to be engaged only in the opening 31 for which it is intended. The table will then be locked in position until it is again desired to close the combined 10 table and cabinet.

While but one form of the invention has been shown and described herein, it will be readily apparent to those skilled in the art that many minor modifications may be made without departing from the spirit of the invention or the scope of the appended claim.

What is claimed is:

In a folding table cabinet, the combination which comprises a casing having hinged doors, 20 vertically disposed rails with horizontally positioned outwardly extended upper ends in opposite sides of the cabinet and positioned in the rear thereof, horizontally disposed rails with supporting diagonally positioned braces also positioned 25 in opposite sides of the cabinet, means hinging the said horizontally disposed rails and braces in the cabinet with the hinged ends of the rails positioned to coact with the horizontally disposed

upper ends of the said vertically disposed rails, said horizontally disposed rails having upwardly extended flanges and horizontally positioned base flanges with openings in the said base flanges, a plurality of transversely positioned hinged slats with spaced grooves in the under surfaces thereof positioned on the horizontally disposed rails with the edges of the said upwardly extended flanges positioned in the grooves in the under surfaces of the slats, said slats mounted to slide inwardly of the cabinet and downwardly behind the said vertically disposed rails, and hooks carried by the slats and positioned to extend into the openings of the horizontally disposed flanges of horizontally disposed rails for retaining the said slats in operative position on said rails.
